UNITED STATES PATENT OFFICE.

ALFRED L. WELHAM, OF TWO RIVERS, WISCONSIN, ASSIGNOR TO HAMILTON MANUFACTURING COMPANY, OF TWO RIVERS, WISCONSIN, A CORPORATION OF WISCONSIN.

RUNWAY STRUCTURE.

1,121,699.

Specification of Letters Patent.

Patented Dec. 22, 1914.

Application filed April 27, 1912. Serial No. 693,599.

To all whom it may concern:

Be it known that I, ALFRED L. WELHAM, citizen of the United States, residing at Two Rivers, in the county of Manitowoc and State of Wisconsin, have invented a certain new and useful Improvement in Runway Structures, of which the following is a full, clear, concise, and exact description, reference being had to the accompanying drawings, forming a part of this specification.

My invention relates to those articles of furniture which include runways for the support of drawers, sliding shelves, etc., and has for its object the provision of an improved mechanical inter-relation between the runways and their supports whereby the assemblage of these parts is simplified and the union therebetween is made more secure.

In practising my invention I employ a framework that includes side members made up of sheet metal, these side members being slotted in the planes of the runways. The runways are inserted through the slots in the said members so as to project into the space between the side members where they may support the drawers or other sliding objects, portions integral with the runways remaining upon the outsides of the side members where such portions are suitably held in fixed relation with the side members.

In the preferred embodiment of the invention the runways are angular in cross section, being desirably made of angle iron that is desirably rolled to a degree of thinness that approximates that of the side members of sheet metal. One leg of each angle iron element is projected horizontally through a slot of the side member that is to support it, the other leg of such angle iron structure being vertically disposed and engaging the associate side member upon its exterior surface. The vertical legs of the angle iron elements may be spot welded to the side members that are preferably made of sheet steel, the angle iron elements being also preferably made of a similar grade of steel. The welding may be reinforced by vertically disposed cleats suitably pressed against the vertical legs of the angular elements and which cleats are in turn suitably held in position as by means of rivets fastening them to the side members, external bracing walls being also desirably employed for holding the cleats in position.

I will explain my invention more fully by reference to the accompanying drawing showing the preferred embodiment thereof and in which—

Figure 1 is a sectional plan view of a cabinet framework structure taken on line 1 1 of Fig. 2; Fig. 2 is a sectional elevation on line 2 2 of Fig. 1; Fig. 3 is a sectional view on line 3 3 of Fig. 1; and Fig. 4 is a view on a larger scale of a part of the structure as shown in Fig. 2.

Like parts are indicated by similar characters of reference throughout the different figures.

The framework includes two main upright side members 1 that are provided with slots 2 extending from the back to the front and which are generally horizontally disposed. These side members are riveted to a back member 3, also preferably made of sheet metal, and are suitably secured to the bottom member 4, whereby the uprights are properly positioned. Runways are projected from the exterior of the framework through the slots 2, these runways being desirably made of metal angle elements, legs 5 of which being projected inwardly through the slots 2 while the legs 6 thereof engage the exteriors of the side members 1, as shown most plainly in Fig. 4. It will be observed that the slots 2 terminate short of the vertical edges of the upright side members 1 so that the portions of the side members which intervene between the substantially horizontal slots 2 are held in relation by the portions of the side members that intervene between the ends of the slots and the vertical edges of the side members.

For mechanical reasons the legs 6 desirably project upwardly, spot welding being employed for holding the metal angle elements in fixed relation with the side members, where the angle elements and side members are made of iron.

Supplemental side members 7 are preferably provided, these supplemental side members being secured to the back member 3 and to the channel iron cleats 8 that separate the main side members 1 from the supplemental side members 7. The cleats 8 are riveted or otherwise suitably fastened to the main and supplemental side members and serve to prevent separation between the vertical legs 6 of the runways and the main

side members 1 whereby the horizontal shelf portions 5 of the runways cannot be thrust outwardly.

The bottom surfaces of the shelf portions 5 of the runways are engaged by the bottom edges of the slots 2 so that downward slippage of the runways is prevented in the event of any breakage of the welds or rivets that are initially provided for holding the 10 vertical legs 6 of the runways and the main side members 1 together. The legs of the angle irons which are upon and engage the exterior surfaces of the side members 1 constitute the preferred form of enlargements 15 for preventing the runways from being passed inwardly completely through the slots and the preferred means whereby the fastening elements 8 serve to hold the runways in position, though I do not wish to be limited, in all embodiments of the invention, 20 to this precise characteristic. By the construction disclosed the assembly of the parts is easily effected since the runways are merely inserted through the slots from the 25 exteriors of the side members 1 and the enlargements of these runways that are upon the exteriors of the side members are engaged by retaining or fastening means that are made separately from the side members 30 1 and are suitably positioned when the side members have received the runways.

**Copies of this patent may be obtained for five cents each, by addressing the "Commissioner of Patents,
Washington, D. C."**

While I have herein shown and particularly described the preferred embodiment of my invention I do not wish to be limited to the precise details of construction shown 35 as changes may readily be made without departing from the spirit of the invention.

Having thus described my invention I claim as new and desire to secure by Letters Patent the following:—

The combination with two supporting upright side members of sheet metal having substantially horizontal runway receiving slots cut therethrough extending between and terminating short of the upright edges 45 of said side members; metallic runways of angular formation in cross section having legs projecting through said slots in the supporting side members into the space between the side members and having their 50 remaining legs upon the exteriors of the side members; and fastening devices engaging the latter legs to hold them in fixed relation with the side members.

In witness whereof, I have hereunto subscribed my name this 23 day of April A. D., 1912.

ALFRED L. WELHAM.
